UNITED STATES PATENT OFFICE.

RICHARD M. JUDD, ERNEST C. TAYLOR, AND RALPH S. McNANEY, OF DOWAGIAC,
MICHIGAN, ASSIGNEES TO PREMIER WARM-AIR HEATER COMPANY, OF DOWAGIAC,
MICHIGAN, A CORPORATION OF MICHIGAN.

CASING HANGER.

Application filed January 24, 1927. Serial No. 163,221.

This invention relates generally to warm air furnaces and refers more particularly to the construction of the casings surrounding such furnaces.

5 Heretofore it has been the practice to provide warm air furnaces with outer casings having inner liners spaced therefrom so as to provide air insulating spaces surrounding the furnaces. However, unless 10 sufficient means were provided for holding the walls in spaced relation there was a tendency for the inner liner to contact with the wall of the casing with the result that the inner liner would burn out due to the 15 intense heat radiating from the combustion chamber of the furnace. It has also been found that there was a tendency for the inner liner to drop down out of place and thereby stop the flow of the cold air to the 20 furnace.

With the present invention, however, these objectionable features are entirely eliminated by providing means for positively supporting and spacing the inner liners 25 from the casings so that there will be no possibility of one wall moving into contact with the other or of the liner dropping down out of alignment with respect to the casing.

With these and other objects in view the 30 invention resides in certain novel features of construction, combinations and arrangements of parts, as will be hereinafter more fully described and particularly pointed out in the appended claims.

35 In the drawings:

Figure 1 is a section through a warm air furnace showing a casing and inner liner arranged in accordance with the present invention,

40 Figure 2 is a detailed view of the inner liner hanger,

Figure 3 is a detailed view of the casing spreader.

In the accompanying drawings wherein 45 like characters of reference designate like parts, the numeral 1 indicates a warm air furnace, 2 the outer casing therefor and 3 an inner liner spaced from the casing so as to provide an insulating air space. In 50 order to adequately support the inner liner 3 and space the same from the casing 2, there are provided hangers 4 positioned ad-

jacent the bottom of the liner and casing spreaders 5 located at the top portions thereof.

As shown, the outer casing 2 is composed of upper and lower sections 6 and 7, respectively, having a central casing ring 8 interposed therebetween, which supports the inner liner hangers 4. These hangers are adapted 60 to be hung at spaced intervals from the casing ring 8 in sufficient quantities to adequately support the inner liner and uniformly space the same from the casing.

Each hanger consists of an elongated body 65 9 which, when placed in position, lies in close proximity to the inner face of the casing 2. As shown, the upper end of the body 9 terminates in a hooked portion 10 which is adapted to be hung over the central casing ring 8 for supporting the hanger in place. The lower end of the body 9 is extended inwardly so as to form a diagonal portion 11 which is provided with a lateral flange 12 having a returned bent portion 13. 70 This portion 13 is in turn provided with a lateral upwardly extending flange 14, adapted to lie in a plane substantially parallel with the body 9 so that its end portion will be spaced from the diagonal portion 11. 80

With this construction the lower end portion of the inner liner 3 is adapted to be supported in a V-shaped opening 14' formed by the flange 14 and the diagonal portion 11 and because of this V-shaped formation 85 the lower edge of the liner is firmly and securely wedged therein.

At the upper edges of the casing 2 and inner liners 3, there are provided a plurality of casing spreaders 5 which are positioned at spaced intervals similarly to the hangers 4. As shown, each spreader consists of a channel-shaped member 15 which is adapted to be placed between the outer casing and inner liner, the walls of the 95 channel 15 being provided with outwardly extending portions 16 overlying the top edges of the casing and inner liner and extending downwardly in contact with the outer walls thereof.

100 In erecting the casing and assuming that the furnace is set up and that the base ring is levelled and in place, the lower section 7 is first put in position after which the cen-

tral casing ring is fitted onto the top edges thereof. The hangers 4 are next placed upon the central ring after which the inner liner is positioned so that the lower edges 5 thereof are securely held in the V-shaped openings 14'.

When this is accomplished the upper section 6 of the outer casing is placed outside of the inner liner, whereupon the spreaders 10 5 are positioned at spaced intervals so as to hold the upper edges of the casing and liner in spaced relation.

It will, of course, be understood, in assembling the casing that arrangements will also be made for taking care of the other sections 15 of the furnace which are not a part of the present invention and which are therefore not herein described.

While the hangers and spreaders are preferably made of galvanized iron, and other suitable material may be used if found more desirable. We have also found it advisable to provide strengthening ribs in the elongated body 9 and in the base portion of each 25 spreader 5, but this is of course optional and need not be resorted to.

From the foregoing it will be apparent that we have provided means for positively supporting and spacing the inner liners from the outer casings of warm air furnaces, 30 which are simple in construction, cheaply manufactured and which will greatly facilitate the assembly of the casings.

While it is believed that from the foregoing description, the nature and advantage of our invention will be readily understood, we desire to have it understood, that we do not limit ourselves to the specific construction herein shown and described and that such 40 changes may be resorted to when desired as fall within the scope of the claims.

What we claim as our invention is:

1. A hanger for the inner liner of a furnace casing comprising an elongated body 45 having a return-bent portion at one end thereof for attachment to the casing and hav-

ing the other end thereof provided with an offset portion adapted to receive an edge of the inner liner for supporting the same and for spacing the liner relative to the casing. 50

2. A hanger for the inner liner of a furnace casing comprising a body having one end thereof provided with a diagonally extending offset portion having a lateral flange, said flange having a return-bent portion 55 provided with a lateral projection cooperating with the aforesaid diagonally extending offset portion to form therewith a wedge-shaped opening for receiving an edge of the said inner liner and for holding the 60 same in spaced relation to the casing.

3. A hanger for the inner liner of a furnace casing comprising a body portion adapted to engage the inner surface of said casing and having its lower end provided 65 with a wedge-shaped opening adapted to receive the lower edge of the inner liner for supporting the same, the upper end of said hanger being provided with a return bent portion for attachment to the casing. 70

4. A hanger for the inner liner of a furnace casing comprising a body having one end thereof provided with a wedge-shaped opening adapted to receive an edge of the inner liner for supporting the same, and a 75 transverse portion extending from the base of said opening to said casing for spacing the liner from the casing.

5. A hanger for the inner liner of a furnace casing comprising a body adapted to be 80 supported by the casing, said body being provided with an offset portion adapted to receive an edge of the inner liner for supporting the same and means projecting from said offset portion to said casing for spacing 85 the liner from the casing.

In testimony whereof we affix our signatures.

RICHARD M. JUDD.
ERNEST C. TAYLOR.
RALPH S. McNANEY.
